UNITED STATES PATENT OFFICE.

MERVIN WILMER TOZER, OF CORTEZ, COLORADO.

CLOSURE FASTENER.

Application filed September 22, 1924. Serial No. 739,126.

To all whom it may concern:

Be it known that I, MERVIN W. TOZER, a citizen of the United States, residing at Cortez, in the county of Montezuma, State of Colorado, have invented certain new and useful Improvements in Closure Fasteners, of which the following is a specification.

This invention relates in general to closure fasteners and is particularly designed 10 for use in fastening covers on shipping crates, boxes, or the like.

The object of the invention is the provision of a fastening device of this character which may be easily and quickly operated to 15 firmly secure the cover or the like to the crate or box and which may also be easily released to permit removal of the cover, the fastening device being permanently mounted on the box or crate and being adapted to 20 be used over and over again.

A further object is the provision of a fastening device having the advantages and capacities mentioned and which is of simple and durable construction, reliable and effective in operation, easy and convenient to apply and remove, and comparatively inexpensive to manufacture.

Other objects and advantages reside in certain novel features of the construction, 30 arrangement and combination of parts which will be hereinafter more fully described and particularly pointed out in the appended claims, reference being had to the accompanying drawing forming a part of this 35 specification, and in which:

Figure 1 is a perspective view showing a shipping crate having the fastening device embodying the present invention organized therewith,

40 Figure 2 is a fragmentary view in elevation of the front side of one end of the shipping case,

Figure 3 is a view in front elevation of a locking lever employed,

45 Figure 4 is a view thereof in edge elevation, and

Figure 5 is a view in perspective showing a locking lever designed for use with a padlock.

50 Referring to the drawings, wherein for the sake of illustration is shown the preferred embodiment of the invention, the numeral 10 designates generally a shipping case having a removable cover 11.

55 The fastening device which constitutes the present invention comprises a pair of

wires 12 encircling the case and the cover adjacent the ends thereof. One end of each wire is formed with a loop 13 and adjacent the loop 13 such wire is fastened, as at 14, 60 to the front wall of the shipping case 10. Intermediate its ends each wire is similarly fastened to the back wall of the shipping case. A locking lever 15 is provided for each wire 12. Each locking lever 15 comprises a shank or bar 16 having oppositely extending and laterally directed lugs 17 and 18 at one end. The lugs 17 are pivotally connected to the loops 13 of the wires 12 and the lugs 18 are pivotally connected to loops 70 20 formed on the wires 12 at the ends thereof opposite the loops 13. A keeper 21 in the form of a loop is provided at the end of the shank 16 opposite the lugs 17 and 18.

With this arrangement the portions of the 75 wires 12 above the fasteners 14 may be swung over the cover 11 as shown in Figure 1 or may be swung to one side of the case as shown in Fig. 2. When swung over the cover 11 as shown in Figure 1 the locking 80 lever 15 may be turned in a clockwise direction to draw the ends of the wire toward each other, thereby tightening the wire on the shipping case and around the cover. If it is desired to release the wires it is necessary to swing the locking levers in a counter-clockwise direction. By engaging the keepers 21 with the wires 12 as shown in Figure 1 the wires may be held in tight engagement with the cover and case. If desired a number of crimps 12^a may be embodied in the wires 12 to give the wires the requisite degree of longitudinal resiliency or elasticity.

In Figure 5 a slightly modified form of 95 locking lever is shown, the shank of the locking lever being designated at 16^a and having a U-shaped keeper 25 at its upper end. The legs of the U-shaped keeper are designated at 26 and are provided with 100 aligned openings 27 designed to receive the shackle 28 of a padlock 29. This lever shown in Figure 5 is designed to be organized with the wires 12 in exactly the same manner as the levers 15, the lever of Figure 105 5 being identical with the levers 15 except that the keeper at its upper end is designed to coact with the padlock.

I claim:

1. A fastener for securing a cover to a 110 shipping case or the like and comprising a binding element encircling the cover and

- case and secured to the case, the upper portion of the binding element being designed to be slipped off the cover when the binding element is released, and a locking lever including a shank having oppositely directed lugs at one end, the lugs being pivotally connected to the ends of the binding element, and a keeper formed on the shank opposite the lugs and adapted to engage with the binding element to hold the same in tight engagement with the cover and case.
2. A fastener for securing a cover to a shipping case or the like and comprising a pair of binding elements, one such binding element being located adjacent each end of the case, one end of each binding element being provided with a loop, means for securing each binding element to the front wall of the case adjacent the loop, a loop on the opposite end of each binding element, and a locking lever connected with the loops of each binding element and co-operable with the binding element to which it is connected for holding the same taut.
3. A fastener for securing a cover to a shipping case or the like and comprising a wire encircling the case and cover, a locking lever having oppositely directed and laterally extending lugs at one end, the lugs being pivotally connected with the ends of the

wire, and a keeper formed on the lever at the end opposite the lugs and engageable with the wire adjacent one end to hold the same taut.

4. A fastener for securing a cover to a shipping case or the like and comprising a wire encircling the case and cover, a locking lever having oppositely directed and laterally extending lugs at one end, the lugs being pivotally connected with the ends of the wire, and a keeper formed on the lever at the end opposite the lugs and engageable with the wire adjacent one end to hold the same taut, said wire having crimps to give the same longitudinal elasticity.

5. A fastener for securing a cover to a shipping case or the like and comprising a wire encircling the case and cover, a locking lever having oppositely directed and laterally extending lugs at one end, the lugs being pivotally connected with the ends of the wire, a keeper formed on the lever at the end opposite the lugs and engageable with the wire adjacent one end to hold the same taut, said keeper being of U-shaped form and having its legs provided with aligned openings, and a padlock having a shackle engageable with said openings.

MERVIN WILMER TOZER.
